UNITED STATES PATENT OFFICE.

ISIDOR K. TRAU, OF LOUISVILLE, KENTUCKY.

REISSUED

CAP

1,414,797.

Specification of Letters Patent.

Patented May 2, 1922.

Application filed January 12, 1922. Serial No. 530,121.

To all whom it may concern:

Be it known that ISIDOR K. TRAU, a citizen of the United States, residing at Louisville, in the county of Jefferson and State of Kentucky, has invented certain new and useful Improvements in Caps, of which the following is a specification.

This invention relates to garments and has special reference to a cap.

10 More particularly the invention relates to a cap having means for adjusting the same to heads of various sizes.

One important object of the invention is to improve the general construction of adjustable caps.

20 A second important object of this invention is to provide an improved construction of adjustable cap wherein the adjusting means will be of such character that it is simple of construction and may be made of ordinary stock parts.

A third important object of this invention is to provide an improved form of cap of the class described wherein the adjusting means will not produce, when the size of the cap is reduced, unsightly or uncomfortable folds or bulges in the cap material.

With the above and other objects in view, the invention consists in general of certain 30 novel details of construction and combinations of parts hereinafter fully described, illustrated in the accompanying drawings, and specifically claimed.

In the accompanying drawings, like characters of reference indicate like parts in the several views, and:

Figure 1 is a front view of a cap constructed in accordance with this invention, the adjusting means being shown in full lines in one position and in dotted lines in a second position.

Figure 2 is a vertical longitudinal section on the median plane of the cap.

Figure 3 is a section on the line 3-3 of Figure 1.

Figure 4 is a face view of the sizing strip forming part of the adjusting means for the cap.

In the construction of a cap in accordance 50 with the present invention there is employed the usual body 10 and vizor 11. At each side the body is slit from the bottom edge upwards as shown at 12, the slits extending

upward for about one inch so as to terminate above the upper edge of the band portion of the cap.

Sewed to one side of the cap just back of the slit 12 is one end of a flexible band 13 whereon is secured, as by fasteners 14, a metallic strip or band 15 provided with a series 60 of spaced snap buttons 16. Above these buttons 16 are suitable indicia to show which button is to be used to adjust the cap to a given size.

Sewed to the other side of the cap just 65 behind the slit 12 on that side is the rear end of a flexible band 17 which is provided, adjacent its free end, with a snap eye 18 of the proper size to fit the buttons 16. This band 17, as well as the band 13 are led 70 through keeper straps 19 sewed to the front of the cap.

The cap is also provided with a snap button 20 on the vizor 11 and a snap eye 21 on the front of the cap so that the front may be 75 buttoned down, as shown in Figure 2, and thus conceal the adjusting means.

The adjustment of this cap from one size to another is readily effected by lifting the front of the cap and then shifting the snap 80 eye from one to another of the buttons 16 after which the cap front is again snapped down. Moreover this adjustment is effected with out producing bulges or folds which are either unsightly or uncomfortable since the 85 slits 12 permit a certain amount of overlapping of the front and back parts of the cap at the band portion.

There has thus been provided a simple and efficient device of the kind described and for 90 the purposes specified.

Having thus described the invention, what is claimed as new, is:-

1. A cap of the character described, having a body provided with slits extending upward from its bottom edge, straps extending from the rear edges of the slits and overlapping in front of the body, a strip secured to the face of one of the straps and provided with spaced snap button members mounted 100 thereon at predetermined size intervals, said strip having size indicia impressed on the strip adjacent the respective snap button members and a cooperating snap button member on the other strap. 105

2. A cap of the character described, hav-

ing a body provided with slits extending upward from its bottom edge, straps extending from the rear edges of the slits and overlapping in front of the body, a rigid strip secured to the face of one of the straps and provided with spaced snap button members mounted thereon at predetermined size in-

ervals, said strip having size indicia impressed on the strip adjacent the respective snap button members and a cooperating snap button member on the other strap.

In testimony whereof I affix my signature.

ISIDOR K. TRAU.
